HEADBAND CONNECTOR

Frank Ostolaza, Florissant, and Glenn Ellery Holmes, St. Louis, Mo., assignors to Mexican American Hat Company, St. Louis, Mo., a corporation of Missouri

Application August 29, 1946, Serial No. 693,723

3 Claims. (Cl. 2—183)

1

This invention relates to improvements in head or sweat band structures for hats, helmets and the like, and has particular reference to novel and effective means affording ready adjustability of the band to accommodate various head sizes. The present invention represents an improvement upon the head band construction as shown and claimed in Patent No. 2,340,980 to Ostolaza and Holmes, issued February 8, 1944.

The principal object of the invention resides in the provision in a head or sweat band structure which may have the form and hat mounting arrangement as shown by the aforesaid patent, of a novel and particularly effective sweat band connector means which is of a character to facilitate ready and quick connection and disconnection of the free ends of the band, and to afford firm connection of the band ends upon perimetral adjustment of the band to accommodate any given head size.

Other objects and advantages of the invention will appear readily from the following description of a presently preferred embodiment thereof, as such is illustrated by the accompanying drawing, wherein:

Fig. 1 is a view in perspective, of a hat having therein a head band embodying the present improvement;

Fig. 2 is an enlarged view of the hat looking toward the crown interior, clearly illustrating the present band connector provision;

Fig. 3 is an enlarged fragmentary perspective of the band at the terminal ends thereof, showing the band connector structure, the view illustrating the band ends in detached condition;

Fig. 4 is a somewhat enlarged transverse sectional view of the connector strap, as taken along line 4—4 in Fig. 3, and

Fig. 5 is a fragmentary, on-edge view of the band at its terminal ends, showing the connector in assembly connection of the band ends.

Referring to the drawing, Figs. 1 and 2 illustrate a hat or helmet A providing a crown 10 and a brim 11. Within the lower crown portion 12 is arranged a head band structure comprising a head or sweat band 14 formed of suitable flexible material and having opposed terminal ends 15 and 16, and band supports or holders 18. As shown, each of the holders 18 is constructed of a relatively thin sheet of semi-rigid, yet flexible material such as fibre, having an extended longitudinal marginal portion 19 through which the holder is secured in hinged relation, to the inner face of the lower crown portion 12, such being effected by suitable stitching or according to pres-

2

ent preference, by eyelet rivets or the like indicated at 20. The body 22 of each holder is provided with spaced slots 23, and through these slots is threaded the head band 14, the band being displaceable therethrough to permit perimetral adjustment thereof for adaptation of the band to a given head size. Except for the provision affording connection of the terminal ends of the head band, which constitutes the subject of the present invention as will appear presently, the character of head band support as above described, is fully disclosed as to structure and advantages thereof, in the hereinbefore mentioned Patent No. 2,340,980.

15 Turning now to the provision herein for facilitating ready and quick disconnection and connection of the terminal ends of the head band, as for the purpose of and to permit ready perimetral adjustments of the head band to adapt 20 the same to various head sizes, there is provided a connector device 24 (Fig. 3) including a strip or tape element 26 of suitable flexible material, having one end portion 27 thereof suitably secured to the head band end 15, as by staples 28. The 25 tape 26 extends forwardly from the band end 15, and is lapped over a relatively thin strip 30 of a semi-rigid bendable material, having a length substantially coextensive with the free length of the tape. The tape 26 and element 30 are secured 30 together in any desired manner, as by an adhesive indicated at 29 in Fig. 4, or by staples or other means, such that the element is substantially covered by or sheathed in the tape. By present preference, the material of strip 30 is a suitable soft metal characterized by ready bendability and yet by sufficient rigidity to hold the bent shape thereof obtaining in effective connection of the head band ends as will appear, against the tensional stressing of the band upon application 40 and use of the hat on the head of the wearer.

The opposed end 16 of the head band presents an opening 31 therethrough, here provided by an eyelet 32 attached to the band end, through which is passed the connection device 24 in the connection 45 of the band ends. Although not herein illustrated, the end 16 of the band may be otherwise adapted for receiving the member 24 in band connection, as for example, by forming the band end 16 as a loop or securing thereto a separate 50 loop element.

Upon perimetral adjustment of the head band, as by displacement of the band through the slots of the holders 18 to expand or contract the effective size of the band, the device 24 is inserted 55 and passed through the eyelet 32, and thence

bent rearwardly or substantially upon itself, thereby coupling or connecting the band ends 15 and 16 in the adjusted position of the band. In effecting the connection, it is to be observed that the device 24 is applied to the band end 16 such that the reversely bent end portion 34 thereof lies on the side of the band opposite to the side or surface 35 thereof which in hat use, engages the head of the wearer, whereby the bent end 34 of the connector is thus effectively shielded from contact with the wearer's head. To the same end, the tape end 27 is secured upon the outer side of the band at its end 15 as such appears in the drawing.

Whenever it may be desired to readjust the perimetral extent of the head band, as to accommodate a smaller or larger head size, disconnection of the band ends is readily and quickly attained merely by bending the connector portion 34 forwardly and thence removing the connector through the eyelet 32. The band is then free for perimetral adjustment, and when such is made, reconnection of the band ends is effected in the manner hereinabove described.

Having now described the invention in respect to the illustrated presently preferred embodiment thereof, what we desire to claim and secure by Letters Patent is:

1. In a hat, a flexible head band having free ends, means mounting the band in the hat and permitting perimetral adjustment of the band for adaptation thereof to a given head size, one free end of the band being provided with an opening therethrough, a tape of flexible material having one end secured to the other free end of said band, and a strip element of a semi-rigid, bendable metallic material arranged along and secured to said tape, said tape and strip element in any perimetral adjustment of the band, being insertible through said opening and serving upon bending of the strip element substantially upon itself, to connect the ends of the head band.

2. In a hat, a head band having terminal ends, and a device for releasably connecting the terminal ends of the head band with the band ends relatively spaced to any selected extent within

a given range, comprising a flexible tape element, means securing one end of the tape element to one terminal end of the band, a strip element of a semi-rigid material characterized by ready bendability, arranged along said tape element and carried thereby, and a single eyelet in the other of said band terminal ends for receiving therethrough said tape carried strip element, said tape and strip elements upon bending of the latter element reversely toward said one terminal end of the band, serving releasably to connect the terminal ends of the band.

3. In a hat, a head band having terminal ends, and a device for releasably connecting the terminal ends of the head band with the band ends relatively spaced to any selected extent within a given range, comprising a flexible tape element, means securing one end of the tape element to one terminal end of the band, a metallic strip element arranged along and carried by said tape element, said metallic strip element being characterized by ready bendability and sufficient rigidity to retain the effected shape thereof in connection of the band ends, under stressing of the head band in normal use, and a single eyelet in the other of said band terminal ends for receiving therethrough the tape carried strip element, said tape and strip elements upon bending of the latter element reversely toward said one terminal end of the band, serving releasably to connect the terminal ends of the band.
